TIRE

David M. Overstreet, Akron, and Robert L. Davis, Mogadore, Ohio, assignors to The General Tire & Rubber Company

Continuation-in-part of design application Ser. No. 15,069, Dec. 20, 1968, which is a continuation-in-part of design application Ser. No. 11,365, Apr. 8, 1968. This application Nov. 24, 1969, Ser. No. 20,267

Term of patent 14 years

Int. Cl. D12—15

U.S. Cl. D90—20

FIG. 1 is a view of the tire in perspective showing our new design, it being understood that the sidewall configuration as shown continues around the entire side peripheral surface of the tire, and that the sidewall opposite to that shown is the same except that the diamond and color bands are not included.

FIG. 2 is an enlarged partial view of the sidewall of the tire shown in FIG. 1; and

FIG. 3 is a profile view taken along lines 3—3 of FIG. 2.

This application is a continuation-in-part of copending application Ser. No. D-15,069 filed on Dec. 20, 1968, which was a continuation-in-part of copending application Ser. No. D-11,365 filed on Apr. 8, 1968, both now abandoned.

We claim:

The ornamental design for a tire, as shown and described.
